Charles Lionel Marcus
INVENTOR

BY
Maurice Spindler
ATTORNEY

UNITED STATES PATENT OFFICE.

CHARLES LIONEL MARCUS, OF NEW YORK, N. Y.

VANITY CASE.

Application filed December 12, 1924. Serial No. 755,387.

This invention relates to containers for holding face powder, cosmetics and other like preparations.

An object of the invention is to provide an improved case or box of the character described having means to confine therein loose or powdered cosmetics or the like material so as to prevent accidental spilling of the cosmetic when the case is inverted, for breaking up the cosmetic should the latter become caked, and for conveniently dispensing a desired quantity of the cosmetic for use.

A further object of the invention is to provide an improved case or box of the character described which is constructed of few and simple parts easy and convenient to handle, neat in appearance and practical and efficient to a high degree for the purposes described.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is an elevational view in cross section of a vanity case embodying the invention;

Fig. 2 is a sectional view taken on line 2-2 in Fig. 1 showing the inner compartment top cover; and

Fig. 3 is a fragmentary sectional view of the inner top cover taken on line 3-3 in Fig. 2.

Referring in detail to the drawing, 10 denotes an outer casing or container of a device embodying the invention, said casing 10 being constructed in any well known manner of metal, paper, molded compositions, or of other suitable material. The casing 10 may be of any suitable shape but is preferably circular in cross-section and 50 comprises a body portion or compartment 11 having an upstanding wall 11^a and a suitable cover 12 which may be either fitted to telescope over said body portion 11, or as shown in Fig. 1, hinged thereto as at 13.

To confine a loose or powdered cosmetic 15, such as face powder or the like, in the

compartment 11^a and to prevent spilling of said cosmetic when the casing 10 is accidentally inverted, an inner compartment cover or partition member 14 may be provided. Said member 14 may be made of any suitable sheet material and formed with a threaded rim portion 14^b for engaging with the threaded inner surface 11^b on the side wall 11^a, said threaded parts being preferably of fine pitch to provide a relatively fine feed of the member 14 into the compartment 11. A powder puff 16 of any well known construction may be provided to occupy the space between the member 14 and the cover 12 (see Fig. 1).

A plurality of spaced depressed lips 14^c may preferably be symmetrically arranged on member 14 by stamping and bending or otherwise formed to provide through said member 14 restricted passages 14^d and scoop portions 14^e. It is apparent from the drawing that on screwing the member 14 into the compartment 11, the scoops 14^e serve to break up the cosmetic 15 should the same become caked and also feed a desired quantity of the cosmetic to the upper side of the member 14 where it can be conveniently taken up for use on the powder puff in the well known manner.

Suitable means may be provided on said member 14, as for example raised projections 14^f diametrically arranged in pairs on the upper surface of member 14 to permit convenient turning of said member into the compartment 11.

In using the container, the powder puff 16 is simply removed and the partition member 14 given a slight turn clockwise by applying the finger to the raised projection 14^f. The scoops 14^e break up the adjacent layer of powder should the same be caked, and feed a portion of the powder to the upper surface of member 14 where it may be taken up by the powder puff 16 in the usual manner. The depressed lips 14^c are constructed to normally obstruct the direct passage of the powder from the compartment, thereby eliminating accidental spilling should the casing be inverted.

It will thus be seen that there is provided a device in which the several objects of this invention are achieved, and which is well adapted to meet the conditions of practical use.

As various possible embodiments might be made of the above invention, and as various

changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. In a container of the character described, the combination of a casing having a compartment for retaining a powdered cosmetic, and a top partition member having a threaded engagement with the upstanding side wall of the compartment and adapted to 15 confine the cosmetic therein, said member having depressed lips to provide restricted passages for feeding the cosmetic to the outer surface of said member on movement thereof with respect to said compartment and for 20 preventing accidental spilling of the cosmetic from the compartment.
2. In a container of the character described, the combination of a casing having a compartment for retaining a powdered cosmetic, and a top partition member having a threaded engagement with the upstanding side wall of the compartment and adapted to 25 confine the cosmetic therein, said member having depressed lips to provide restricted 30 passages for feeding the cosmetic to the outer surface of said member on movement thereof with respect to said compartment and for preventing accidental spilling of the cosmetic from the compartment, and means on 35 said member to facilitate the said movement thereof with respect to said compartment.
3. In a container of the character described, the combination of a casing having a compartment of circular cross-section for 40 retaining a powdered cosmetic, and a top partition member for confining the cosmetic in the compartment, said member being movably mounted in said compartment and having a threaded rim adapted to engage with a 45 threaded portion of the upstanding wall of said compartment, and depressed lips to provide 50 through passages for feeding the cosmetic to the outer surface of said member on turning thereof in the said threaded connection, said lips having scoop portions arranged to restrict said passages for preventing 55 accidental spilling of the cosmetic from the compartment and to positively feed the cosmetic through the passage on said turning of the member.

4. In a container of the character, described the combination of a casing having a compartment of circular cross-section for retaining a powdered cosmetic, and a top 60 partition member for confining the cosmetic in the compartment, said member being movably mounted in said compartment and having a threaded rim adapted to engage with a threaded portion of the upstanding wall of 65 said compartment, and depressed lips to pro-

vide through passages for feeding the cosmetic to the outer surface of said member on turning thereof in the said threaded connection, said lips having scoop portions arranged to restrict said passages for preventing accidental spilling of the cosmetic from the compartment and to positively feed the cosmetic through the passage on the said turning of the member, and raised projections on said member to facilitate screwing 75 said member into the compartment.

5. In a container of the character described comprising a casing having a compartment for retaining a powdered cosmetic, a rotary top partition member for confining the cosmetic in the compartment and connecting means for positively feeding the member into the compartment on the rotation of said member, said member having openings therein to permit passage of the cosmetic during the said rotation of the member, said opening constructed to prevent the accidental spilling of the cosmetic from the compartment when the case is inverted.

6. In a container of the character described, a casing having a compartment for retaining a powdered cosmetic, a rotary top partition member for confining the cosmetic in the compartment and connecting means for positively feeding the member into the compartment on the rotation of said member, said member having openings therein to permit passage of the cosmetic during the said rotation of the member, and spaced projecting portions on the outer surface 95 of said member to facilitate the rotation thereof.

7. In a container of the character described, a casing having a powdered cosmetic compartment, a top partition member for confining the cosmetic in the compartment, a screw means for feeding the member into the compartment, said member having openings therein to permit forced passage of the cosmetic therethrough during the feeding of said member into the compartment.

8. A powder box including a case, a closure therefor, a partition adjustably mounted in the case to extend thereacross to divide said case into an open compartment and a closed compartment, said closed compartment adapted to contain a powder toilet preparation, there being openings through the partition through which some of the powder will be forced into the open compartment when the said partition is adjusted in the same case in one direction, and means by which the said partition may be adjusted at will and to any desired extent within the case and maintained in its adjusted position.

9. A powder box including a case, a closure therefor, a partition in the case to extend thereacross to divide said case into an open compartment and a closed compartment, said closed compartment adapted

to contain a powder toilet preparation, means mounting the partition for adjustment within the case and for maintaining the partition in its adjusted position, there being openings through the partition through which some of the powder will be forced into the open compartment when the said partition is adjusted in the said case in one direction, and formations on the partition disposed within the said case and by means of which formations the said partitions may be adjusted with respect to the case.

10. A powder box including a case, an in-

ternally threaded annular member within 15 the case adjacent the wall thereof, a partition, peripheral threads on the partition to engage the threads in the annular member, said threads operating to feed the partition with respect to the annular member 20 when the partition is rotated, there being openings through the partition for the passage of powder as the partition is rotated, all of said parts being housed within the said case, and a closure for the case. 25

In testimony whereof I affix my signature.

CHARLES LIONEL MARCUS.
